US00D899906S

(12) **United States Design Patent** (10) **Patent No.:** **US D899,906 S**
(45) **Date of Patent:** **** Oct. 27, 2020**

(54) **CABLE CLIP**

(71) Applicant: **Gibraltar Global, LLC**, Burnet, TX (US)

(72) Inventor: **William H. Neusch**, Marble Falls, TX (US)

(73) Assignee: **GIBRALTAR GLOBAL, LLC**, Burnet, TX (US)

(**) Term: **15 Years**

(21) Appl. No.: **29/679,063**

(22) Filed: **Feb. 1, 2019**

Related U.S. Application Data

(60) Continuation of application No. 14/987,617, filed on Jan. 4, 2016, now Pat. No. 10,202,730, which is a continuation of application No. 14/513,207, filed on Oct. 13, 2014, now Pat. No. 9,228,306, which is a continuation of application No. 13/619,613, filed on Sep. 14, 2012, now Pat. No. 8,857,796, which is a continuation of application No. 12/040,322, filed on Feb. 29, 2008, now Pat. No. 8,266,803, which is a division of application No. 11/175,939, filed on Jul. 6, 2005, now Pat. No. 7,398,960.

(57) **CLAIM**

The ornamental design for a cable clip, as shown and described.

DESCRIPTION

FIG. 1 is a first side view of a cable clip showing the new design;

FIG. 2 is a second view thereof;

FIG. 3 is a front view thereof;

FIG. 4 is a back side view thereof;

FIG. 5 is a top view thereof;

FIG. 6 is a bottom view thereof; and,

FIG. 7 is a perspective view showing the cable clip in an example environment.

The portions of the drawings shown in dashed lines form no part of the claimed subject matter.

1 Claim, 4 Drawing Sheets
